UNITED STATES PATENT OFFICE.

WILLIAM F. HOLMES, OF BROCKTON, MASSACHUSETTS.

TOY HORSE.

1,122,929

Specification of Letters Patent. Patented Dec. 29, 1914.

Application filed August 12, 1913. Serial No. 784,389.

To all whom it may concern:

Be it known that I, WILLIAM F. HOLMES, citizen of the United States, residing at Brockton, in the county of Plymouth and State of Massachusetts, have invented certain new and useful Improvements in Toy Horses, of which the following is a specification.

The present invention relates to new and useful improvements in toys, and has particular reference to that type of such devices known as hobby horses.

As its principal object, this invention contemplates the provision of a miniature horse which is mounted on two disk wheels, and is adapted to be straddled by a child, so that his feet may touch the ground and afford means of locomotion.

An object of equal importance with the foregoing is to construct the body portion of the animal in two hingedly connected sections, providing the head portion with a steering column so that the toy may be guided in the desired manner.

A further object is to detachably connect the head portion of the animal's body to the steering column so that, if desired, it may be removed and the remaining portion of the device be employed as an ordinary toy bicycle.

A yet further object is to construct the device of this invention with such regard to number, proportion and arrangement of parts that it may be cheaply manufactured and will be durable and efficient in its action.

The above and additional objects are accomplished by such means as are illustrated in the accompanying drawings, described in the following specification and then more particularly pointed out in the claim which is appended hereto and forms a part of this application.

With reference to the drawings, wherein I have illustrated the preferred embodiment of my invention as it is reduced to practice, and throughout the several views of which similar reference numerals designate corresponding parts, Figure 1 is a side elevation with the head and body portions of the device in assembled relation; Fig. 2 is a side elevation illustrating the head member in detached position; Fig. 3 is a detail perspective view of the head member, illustrating particularly the plates employed in detachably connecting the head to the steering column; and Fig. 4 is a detail view in rear elevation of the steering column in disassembled position.

Proceeding now to the description of the drawings, the numeral 10 designates as an entirety the body portion of the toy horse which is formed in two hingedly connected sections, respectively designated by the numerals 11 and 12. The member 11 constitutes the main body portion of the animal trunk, while the member 12 comprises the head portion, as will be readily observed upon reference to Fig. 2 particularly.

In hingingly connecting the members 11 and 12, there has been provided a steering column 13 which consists essentially in a wooden bar or rod 14. The forward terminal of the member 11 is equipped with a hinge rod 15, the ends of which are journaled in the apertured arms 16 and 17 of a U-shaped hinge plate 18 which is bolted or otherwise secured in any desired manner to the rear face of the steering rod. The head portion 12 is detachably secured to the forwardly disposed face of the steering column by means of a plate 19 carried at the lower end of the member 12 and a pair of additional plates 20 and 21 carried adjacent the upper portion of the neck. The plate 19 extends beyond the rear edge of the member 12 and is equipped with an aperture adapted to fit over a downwardly extending pin 22 mounted in the lower terminal of the steering column. The plates 20 and 21 are bolted or otherwise secured in any desired manner to opposite sides of the neck portion of the member 12 and extend rearwardly thereof, being terminally apertured to receive a pin or rod 23 which is carried transversely of the steering column adjacent its upper terminal. The member 23 is preferably formed with a head 24 and a threaded shank 25 which latter is adapted to be projected beyond the plate 20 to receive a nut 26, which obviously prevents the accidental displacement of the pin, but, at the same time, provides for the complete removal of the head portion 12 from the steering column so that the trunk portion 11 may be employed as a bicycle. In this connection, it is to be noted that a pair of wheels 27 and 28 are respectively carried by the steering column and the rear terminal of the member 11. The wheel 27 is journaled on a spindle 29 which is mounted on the lower terminals of a pair of fork bars 30 and 31 bolted or otherwise secured as may be de-

sired to the opposite faces of the steering column. A pair of rear fork bars, one of which is indicated at 32, is secured to the member 11 adjacent its rear terminal and carry at their lower terminals a spindle 34 on which the wheel 28 is mounted.

A saddle 35 may be secured in any desired manner to the back portion of the member 11, and may be of any desired and 10 suitable design.

As will be observed, a handle bar 36 is carried by the upper terminal of the steering column. A pair of reins may be provided, as indicated at 37.

15 The actual construction and arrangement of the several parts of the device being thus disclosed, it now remains to describe the manner in which the toy is used.

The user of the device straddles the trunk 20 portion 11 which is preferably supported from the ground or floor such a distance as to permit the average child's feet to bear on the supporting surface. By imitating a walking motion, the child may propel the 25 device in a well known manner, and may steer the horse by manipulating the handle bar 36.

It is desirable to again call attention to 30 the fact that the head portion 12 may be detached from the steering column, and the remaining portion of the structure employed as a toy bicycle adaptable for use indoors.

It is obvious, of course, that the body 35 portion of the device may be made in imitation of a giraffe, camel or any other animal as well as a horse, without departing in any way from the main principles of this invention which include boardly the 40 provision of a two piece body hingedly connected and having the head portion detachably secured to a steering column.

From the foregoing, it will be observed 45 that there has been provided a toy which is simple in its construction and may, therefore, be cheaply manufactured. It is to be further noted that this device has been found particularly efficient in teaching children to learn to walk, inasmuch as they 50 become accustomed to using their limbs without having the entire weight of their bodies supported thereby.

It has been found desirable in some instances to adjustably secure the fork arms 55 and wheels 27 and 28 respectively to the

steering member 14 and body member 11 by means of removable bolts 39. By employing removable bolts, it is of course possible to vary the height at which the body of the device is spaced from the ground by 60 shifting the fork-arms on the body and steering column, in a manner which will be apparent upon reference to either Figs. 1 or 2.

In reduction to practice, I have found 65 that the form of my invention, illustrated in the drawings and referred to in the above description as the preferred embodiment, is the most efficient and practical; yet realizing that the conditions concurrent 70 with the adoption of my device will necessarily vary, I desire to emphasize the fact that various minor changes in details of construction, proportion and arrangement of parts may be resorted to, when required, 75 without sacrificing any of the advantages of my invention, as defined in the appended claim.

What I claim is:

In a device of the character described, a 80 body member, a separate head portion, a steering post interposed between the head and body portions, a substantially U-shaped hinge plate secured to the steering post and pivoted at the forward terminal of the body 85 member, a pair of terminally apertured plates secured to opposite sides of the head member, the apertured terminals of the plates extending beyond the rear edge of 90 the head member, a fastening device passing through the steering post and adapted to be received in the apertures of said plates for connecting the head member to the steering post, an attaching plate secured to the lower edge portion of the head member 95 and having its terminal extending beyond the rear edge thereof, said extending terminal being apertured, a stud carried by the lower terminal of the steering post and receivable within the aperture of the last-mentioned attaching plate, a pair of wheels, and fork arms securing the wheels to the body member and steering post.

In testimony whereof I affix my signature in presence of two witnesses.

WILLIAM F. HOLMES. [L. S.]
